UNITED STATES PATENT OFFICE.

EDWARD B. ENTWISLE, OF JOHNSTOWN, PENNSYLVANIA, ASSIGNOR TO
THE JOHNSON COMPANY, OF LORAIN, OHIO.

RAILWAY SWITCH-MATE.

SPECIFICATION forming part of Letters Patent No. 576,564, dated February 9, 1897.

Application filed November 5, 1896. Serial No. 611,123. (No model.)

To all whom it may concern:

Be it known that I, EDWARD B. ENTWISLE, of Johnstown, in the county of Cambria, State of Pennsylvania, have invented certain new 5 and useful Improvements in Railway Switch-Mates, of which the following is a specification.

My invention relates to railway switch-mates; and has for its object the provision of a light, durable, and efficient structure having a combined guard and floor-plate member, 10 preferably of rolled steel, to protect the point of the rail from wear and to act as a safeguard against derailment.

Referring to the drawings, Figure 1 represents a plan view of a switch-mate embodying the features of my invention. Figs. 2 and 15 3 are vertical sections, respectively, on the lines Y Y and X X of Fig. 1.

A is the continuous main-line rail of the mate. B is the curved branch-off rail, with its head tapered in the usual manner, so as to 20 make a point-rail.

C is an ordinary guard-rail section adapted to be secured to the side of a T-rail. D is a 25 combined guard and floor-plate section, also adapted to be secured to the side of a T-rail.

E is a chock, of cast-iron or other suitable material.

w is a washer, and b' b² b³ are bolts or rivets 30 securing together the different parts of the structure.

s is the floor-line of D, and t is a line on the level of the groove-line of guard C.

The flange of rail B, adjacent to A, is tapered 35 to fit against the points of the inside flange of rail A. Between rails A and B is secured the chock E, which fits the contours of both rails, so effecting a more rigid structure. From the point of rail B, E extends longitudinally 40 toward the entrance of the mate and is tapered on its side, so as to afford a bearing for the floor-plate section. Section D extends longitudinally from substantially the point on rail A where the gage-lines of the rails diverge to a point on rail B close to the point 45 where its head begins to taper. It is curved substantially similarly to the curve of rail B and is planed, as shown, so as to bear against the point of B and so as to fit against the side 50 of chock E.

As the curve of D forbids a bearing against the web of the main-line rail the washer w and the tapered extension of E are adapted to effect this end.

The bolt b', passing through A, w, and D, 55 and the bolts b² b³, passing through A, E, B, and D, fasten the whole structure rigidly together.

At each end of D the floor-line is tapered, as shown, from the level s to the level t. I 60 here show the chock E tapered at one end in a similar manner. Instead of this construction, however, I may make a narrow groove through both D and E, said groove being parallel and closely contiguous to rail A. 65

Any ordinary guard-rail section C, curved to fit B, is secured thereto, so as to abut the end of the D section.

If the switch (not here shown) used in conjunction with my improved mate is set for the 70 branch-off track, the wheel-flanges on the mate side of an approaching vehicle will rise on the tapered end of D, and the wheels will not bear on the head of the rail. Instead the wheel-flanges will travel on the line s of the 75 floor-plate section until they reach the full head of rail B, when the wheels will return to their normal position by descending on the tapered end of D.

If the switch be set for the straight track, 80 the wheel-flanges will (using the construction shown in the drawings) rise on the tapered ends of D, travel on D and E, and at the tapered end of E descend again to their normal positions. If the hereinbefore-described 85 narrow groove has been planed out of the top of the D and E sections, the wheels will retain their normal bearing on A while traveling through the mate on the straight track.

It will thus be seen that in my improved 90 mate there is no wear upon the top of the point-rail, all the wear being taken by the hard floor-plate section. Neither is there any danger of derailment due to slight irregularities in the shape or position of the car-wheels. 95

I do not limit myself to the exact details herein described, as modifications may readily be made in the arrangement of parts and other details without departing from the scope of my invention. On the other hand, I do not 100

claim, broadly, a switch-mate in which a floor-plate and guard are provided, for such a mate I am aware has no novelty.

What I do claim, and desire to protect by 5 Letters Patent, is—

1. In a railway switch-mate, a member, as D, having a guard and having a floor upon which the wheel-flanges of the moving vehicle are enabled to roll.
- 10 2. In a railway switch-mate, a renewable rolled section having a guard portion adapted to guide the wheels of the moving vehicle, and a floor upon which the wheel-flanges of said vehicle are enabled to roll.
- 15 3. In a railway switch-mate, in combina-

tion, the renewable rolled section D, the chock E, the guard-rail C, all substantially as, and for the purpose, set forth.

4. As a new article of manufacture, a guard-rail section, adapted to be secured to T-rails, 20 and having a floor adapted to be a running-surface for wheel-flanges, said section being rolled to substantially the shape shown.

In testimony whereof I have affixed my signature in presence of two witnesses.

EDWARD B. ENTWISLE.
